W. Johnson
The Knockdown

WITNESS:

Victor J. Evans
BY

ATTORNEY.

UNITED STATES PATENT OFFICE.

CLARENCE L. HAHN, OF BALTIMORE, MARYLAND.

BOX-OPENER.

1,399,618.

Specification of Letters Patent. Patented Dec. 6, 1921.

Application filed July 20, 1920. Serial No. 397,653.

To all whom it may concern:

Be it known that CLARENCE L. HAHN, a citizen of the United States, residing at Baltimore, in the county of Baltimore City 5 and State of Maryland, have invented new and useful Improvements in Box-Openers, of which the following is a specification.

This invention relates to improvements in openers for boxes or containers and has for 10 an object the provision of means carried by the container, whereby the cover may be easily and quickly removed.

Another object is the provision of a device of this character which may be applied 15 to containers now in use, without employing rivets or the like as a securing means, so that leakage of the contents of the container is avoided.

Another object is the provision of an 20 opener which does not extend beyond the edges of the container and which will therefore not interfere with proper and compact packing.

Other objects and advantages of the invention will appear as the following description is read in connection with the accompanying drawings.

In the drawings:—

Figure 1 is a side elevation view of a container with the invention applied, the container being shown in closed position.

Fig. 2 is an enlarged fragmentary section of the same.

Fig. 3 is a similar view showing the lid 35 or cover raised.

Fig. 4 is a detailed perspective view of the opener removed from the container.

Figs. 5 and 6 are similar views of modified forms of the invention.

Referring to the drawings in detail, 40 wherein like characters of reference denote corresponding parts, the invention is shown as applied to the top of a tin box or container usually employed for holding shoe dressing. The container is indicated by the reference character 10 and is of circular formation, being provided with an annular bead 11 which is spaced from the top edge 45 of the container, the said bead being shown formed by crimping so as to extend laterally around the outer edge of the container.

This bead forms a shoulder stop for a removable lid or cover 12, the latter being provided with a flange 13 for engagement with 50 the bead.

The cover 12 is constructed so as to snugly

fit over the container and extends over the side wall of the latter for an appreciable distance, so as to provide a substantially airtight receptacle, the purpose being to keep 60 the contents of the container in proper position for use. It is therefore, difficult to remove the cover without the aid of some tool or device for insertion between the edge of the cover flange and the bead 11 and for 65 this purpose there is provided a substantially Z shaped metal slide 14. This slide is formed of flat metal and is provided at one end with an inturned lip 15 which, when the cover is in position upon the container occupies 70 a position between the bead and the cover flange. The opposite end of the slide is provided with an outwardly extending lip 16 which provides a finger piece for manipulating the slide. The length of the 75 slide is such that when in its lowermost position, it will not extend below the bottom of the container, while the extremity of the lip 16 lies within the edge of the bead 11. Thus no projecting surfaces are provided, 80 which might interfere with the proper packing of the container for shipment.

The slide 14 operates in a slot 17 provided in the bead 11 and is moved transversely of the width of the container to lift the cover, 85 as illustrated in Fig. 3 of the drawings. In order to prevent the accidental removal of the slide from the slot, the former is provided with a stop 18 which limits its movement in one direction. This stop may be 90 formed in various ways, such as by a drop of solder upon the outer face of the slide as illustrated in Figs. 1 to 4 of the drawings, or it may be formed by punching the material outward as shown at 19 in Fig. 5. 95 This must be done after the slide has been inserted in the slot 17 and various means may be employed for its accomplishment. For example, the male member of a punch may be positioned between the slide and the 100 container with the latter resting upon a corner and a female punch member brought down upon the outer face of the slide.

If desired, the slide may be used without the stop, having merely the lips 15 and 16 as 105 shown in detail in Fig. 6.

In forming the slit 17 in the bead 11, it may be necessary to deposit a drop of solder upon the inside of the box for the purpose of closing an opening which might communicate with the interior of the box 110 through the formation of the slot 17, this

solder being indicated at 20. If, however, the bead 11 is tightly crimped so that its walls are pressed closely together in contacting relation, this solder will not be necessary, as no opening will extend into the receptacle.

The invention is susceptible of various changes in its form, proportions and minor details of construction and the right is herein reserved to make such changes as properly fall within the scope of the appended claims.

Having described the invention what is claimed is:—

- 15 1. The combination with a container having an annular bead spaced from the open upper edge thereof and a removable flanged cover engageable over the container, of a member mounted for sliding movement through an opening in the bead and engageable with the edge of the cover for the removal of the latter.
- 20 2. The combination with a container having an annular bead spaced from the upper edge thereof and a removable flanged cover engageable over the container, of a member mounted for sliding movement through an opening in the bead, a lateral extension carried by said member for position beneath the bead and the edge of the cover, whereby

the cover may be removed through a sliding movement of the member.

3. The combination with a container having an annular bead spaced from the upper edge thereof and a removable flanged cover engageable over the container, of a member mounted for sliding movement through an opening in the bead, a lateral extension carried by said member for position between the bead and the edge of the cover, whereby the cover may be removed through a sliding movement of the member and a stop carried by said member and located upon the opposite side of the bead.

4. The combination with a container having an annular bead spaced from the edge thereof and a removable flanged cover engageable over the container, of a substantially Z shaped member mounted for sliding movement through an opening in the bead, one end of said member being engageable between the bead and the edge of the cover, while the opposite end extends outwardly to provide a finger piece, whereby the cover may be removed through a sliding movement of the Z shaped member and a stop carried by said member to limit its movement in one direction.

In testimony whereof I affix my signature.

CLARENCE L. HAHN.
